UNITED STATES PATENT OFFICE.

ALPHONSO WALRATH, OF FORT PLAIN, NEW YORK.

DESIGN FOR A BROOM-FERRULE.

SPECIFICATION forming part of Design No. 24,705, dated September 24, 1895.

Application filed July 17, 1895. Serial No. 556,293. Term of patent 7 years.

To all whom it may concern:

Be it known that I, ALPHONSO WALRATH, a citizen of the United States, residing at Fort Plain, in the county of Montgomery and State of New York, have invented and produced a new and useful Design for a Broom-Ferrule, of which the following is a specification.

My invention relates to a novel and original design for the ornamentation of a broom-ferrule, which is an article in the nature of a sheet-metal ornamental collar fastened upon a broom to encircle the junction between the broom-corn and handle.

My design is illustrated in the accompanying drawings, in which—

Figure 1 is a plan view of the blank having its surface ornamented with my design, and

Fig. 2 is a perspective view of the ferrule ready to be applied to a broom.

The leading feature of my design consists in the ornamentation of the surface thereof, comprising series of characters formed by indentations.

A is the ferrule, the variety illustrated being that which is provided with a circumferential bead *r* above a circumferential groove *q*. In the surface of the blank I provide, lengthwise thereof and in serial alignment with each other, rows of characters *B*, each of diamond shape or approximately diamond shape and composed of numerous indentations in proper relation to each other. These diamond-shaped characters *B* are provided over the entire surface of the ferrule, thus upon the bead *r* and in the groove *q*, and I prefer to arrange them so that the members of one row will alternate with and overlap those of the next succeeding row.

What I claim is—

The design for a broom-ferrule, substantially as herein shown and described.

ALPHONSO WALRATH.

In presence of—

M. J. FROST,
J. N. HANSON.
